The ornamental design for a foot callous pad, as shown and described.

DESCRIPTION

FIG. 1 is a top plan view of the foot callous pad of the subject invention, the bottom plan view being a mirror image thereof;

FIG. 2 is a front elevational view thereof;

FIG. 3 is a rear elevational view thereof; and,

FIG. 4 is a left side elevational view thereof, the right side elevational view being a mirror image thereof.
